[57] CLAIM

The ornamental design for a combined plant feeder and support stake, as shown and described.

DESCRIPTION

FIG. 1 is perspective view of a combined plant feeder and support stake showing my new design;

FIG. 2 is a front elevational view thereof, the rear elevational view being identical thereto;

FIG. 3 is a right side elevational view thereof, the left side elevational view being a mirror image thereof;

FIG. 4 is a top plan view of the design; and,

FIG. 5 is a bottom plan view thereof.

The tubular portion of the claimed design is shown broken away in FIGS. 2 and 3 for ease of illustration.
